UNITED STATES PATENT OFFICE

110,118

DESIGN FOR A DRESS

Max Frankel, New York, N. Y.

Application April 20, 1938, Serial No. 76,636

Term of patent 3½ years

To all whom it may concern:

Be it known that I, Max Frankel, a citizen of the United States and residing in Manhattan, in the city, county, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the specific shoulders as shown in association with the specific embroidery of shoulders and dress, in combination with the specific dress as shown.

I claim:

The ornamental design for a dress substantially as shown and described.

MAX FRANKEL.
